UNITED STATES PATENT OFFICE.

WILLIAM GOFORTH, OF WINDSOR, MISSOURI.

FASTENER FOR THE MEETING-RAILS OF SASHES.

SPECIFICATION forming part of Letters Patent No. 296,402, dated April 8, 1884.

Application filed April 26, 1883. (Model.)

To all whom it may concern:

Be it known that I, WILLIAM GOFORTH, a citizen of the United States, residing at Windsor, in the county of Henry and State of Missouri, have invented certain new and useful Improvements in Sash-Locks; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to sash-locks; and it consists in the parts which will be hereinafter described, and pointed out in the claim.

In the drawings, Figure 1 is a plan view of my improved lock. Fig. 2 is a sectional view 20 on line xx , Fig. 1. Fig. 3 is a detail view of the stop. Fig. 4 shows a modification, and Figs. 5 and 6 show the circles from which the lock is formed, all of which will be described.

25 One object of my invention is to provide a lever sash-lock wherein the axis or shank of the same may be pivoted on the meeting-rail of the lower sash, while the circular portion of the lever is adapted to be passed around a 30 suitable stop secured on the lower or meeting rail of upper sash, the said lever being so constructed that it will extend around the stop and across the joint between the two meeting-rails, and have its point rested on the same 35 rail to which the latch is pivoted. This may be accomplished by the construction shown in Fig. 4, wherein I employ but a single lever and a stop of a form different from that shown in the other figures.

40 I prefer to use the form of latch and stop shown in Figs. 1, 2, and 3, as will now be described.

I have only shown the meeting-rails of the upper and lower sashes, A B, they being the 45 parts to which the locking mechanism is applied.

The stop a is secured on the lower or meeting rail of the sash A, and is composed of the lower or base portion, a' , and a top plate, a'' , 50 the edges of which top plate project on the opposite sides of the lower portion, a' , and

provide the shoulders a^3 , which are engaged by the levers on the latch, as will be described.

The latch b has its shank b' pivoted on the top of the sash B, and it is provided on its 55 swinging end with the levers b^2 b^3 , which are arranged to extend the one on the outer and the other on the inner side of the lower portion, a' , of the stop a , and under the projecting portions of the top plate, a'' , as shown in 60 Fig. 2. These levers are made sufficiently long to permit them to extend across the joint between the meeting-rails, and thereby strengthen the fastenings and hold the sash firmly together. These levers and the slots between them 65 and the shank portion of the latch are formed in approximately the arc of a circle, the center of which is the pivot-point of the latch, as shown at Figs. 5 and 6. It will be seen, therefore, that all force on the latch to effect the 70 unlocking thereof must be exerted in a line curved concentrically with the curve of the levers. Therefore, in a lever-latch constructed substantially as described, it will be difficult, if at all possible, for the latch to be opened by 75 any instrument inserted between the meeting-rails, as is commonly practiced with sash-locks of ordinary construction.

The latch and the stop may be secured directly on the sashes when so desired; but in 80 order to prevent the insertion of any instruments between the meeting-rails, I prefer to employ the plates c c' , on which are secured, respectively, the stops a and the latch b . The plate c is set back a short distance from the 85 meeting edge of the rail of the sash A, to which it is secured, and the plate c' is secured on the sash B, and is projected over the meeting edge thereof and over the joint between the rails, and prevents anything being slipped 90 between the rails for the purpose of unlocking the sashes. The latch b is provided with a finger-post or handle, d , for the purpose of readily operating the same. The lever is tapered from its point to its junction with the 95 shank so that as it is turned under the stop it will draw the sash, to which the latter is fastened up firmly into place.

Having thus described my invention, what I claim, and desire to secure by Letters Patent, 100 is—

The sash-fastening herein described, com-

posed of the latch having its shank pivoted on the sash B, and provided with the tongue curved on an arc struck from its pivot and beveled from its point upward, and adapted to be swung 5 twice over the joint between sashes A B, and the stop having a lateral ledge or plate projected from its upper end and arranged on sash A in position to be engaged by the latch-lever,

substantially as described, and for the purposes set forth.

In testimony whereof I affix my signature in presence of two witnesses.

WILLIAM GOFORTH.

Witnesses:

G. W. GIVENS,
MAURICE DICK.
